UNITED STATES PATENT OFFICE.

GEORGE W. WELLS, OF AMESBURY, MASSACHUSETTS, ASSIGNOR TO WALKER WELLS COMPANY, OF AMESBURY, MASSACHUSETTS, A CORPORATION OF MASSACHUSETTS.

LOCK.

1,358,404.

Specification of Letters Patent. Patented Nov. 9, 1920.

Application filed May 13, 1920. Serial No. 381,113.

To all whom it may concern:

Be it known that I, GEORGE W. WELLS, a citizen of the United States, resident of Amesbury, in the county of Essex and State of Massachusetts, have made a certain new and useful Invention in Locks; and I declare the following to be a full, clear, and exact description of the same, such as will enable others skilled in the art to which it appertains to make and use the invention, reference being had to the accompanying drawings, and to letters or figures of reference marked thereon, which form a part of this specification.

5 Figure 1 is a perspective view of the invention, with the bolt released and the key in place.

Fig. 2 is a plan view of the invention, with the key removed.

0 Fig. 3 is a section on the line 3—3, Fig. 2, with the key hole cover plate turned down over the key hole.

Fig. 4 is a section on the line 4—4, Fig. 2, with the bolt in locking position.

5 Fig. 5 is a section on the line 5—5, Fig. 2.

Fig. 6 is a face view of the lock with the key in place and in section.

Fig. 7 is a detail perspective view of the key.

0 The invention has relation to deck lid locks for motor cars, and it consists in the novel construction and combinations of parts, as hereinafter set forth.

In the accompanying drawings illustrating the invention, the numeral 2 designates the casing, which is a steel stamping bent up into form and provided with the side plates 3 and 4 spaced apart, the inner plate 3 having end extensions 5, perforated at 6 for attachment screws 7.

5 Fitting and working in the casing is the jaw or bolt 8, a tubular pivot pin 9 rotatably engaging alined perforations 10, 10, of the side plates 3 and 4, and engaging 5 perforation 11 of said jaw or bolt, which has spline connection 12 with said pivot pin.

The tubular pivot pin or barrel has an end extension 13, projecting outwardly, and 0 in line with said extension are studs 14, 14, the latter having reduced inner extensions 15, 15, engaging perforations of the outer casing plate, and at their outer ends said studs are provided with threaded apertures 16.

Fitting over the pivot pin or barrel and the studs is an escutcheon or key-hole plate 17, attachment screws 18 therefor engaging perforations thereof and the threaded apertures of said studs, a key-hole 19 being formed in said plate in line with the outer end of said barrel or pivot pin, which is provided with diametrically opposite open-end notches 20 for the reception of the diametrically opposite lugs 21, of a key 22, 65 said key having a cylindrical stem the outer end of which engages the bore of said pivot pin or barrel.

A key-hole cover plate 23 is hinged to the key-hole plate at 24, and is capable of being turned over the key-hole to protect the same.

The jaw or bolt is made up of a plurality of laminations, suitably secured together to form a unitary whole, and is provided with 75 a hooked outer end portion 25, having a recess 26, designed for engagement with a stud or pin of the deck lid to maintain the same in closed position.

The key-hole is of mutilated circular 80 form, having diametrically opposite arcuate extensions 27, 27, which overlap the outer end of the barrel or pivot pin, and the key being inserted within the bore of the pivot pin or barrel, with its lugs in engagement 85 with the barrel notches, and rotated one-quarter around to withdraw the jaw or bolt within the casing, said lugs will be moved under said arcuate extensions 27, 27, whereby the key will be effectually prevented 90 from withdrawal after its movement as stated to release the jaw or bolt from the locking pin or stud of the deck lid. The deck lid being closed, the key is moved one-quarter around reversely, to engage the jaw 95 or bolt with the securing pin or stud of the deck lid, after which the key may be withdrawn or removed. The key-hole opening is larger than the notches of the barrel or pivot pin, lapping over the said notches at 100 each side thereof, whereby the key may have its lugs readily engaged with said notches.

The jaw or bolt is snapped home to locking or released position by the spring 28, located at the back of the casing and engaging said 105 jaw.

I claim:

1. In a lock, a casing, a jaw or bolt mounted therein and having a tubular pivot pin, the outer end of which is provided with 110

- a notch, a key-hole plate secured to said casing and having a key-hole, the marginal wall of which is provided with an extension, and a key insertible within the outer 5 end of said pivot pin and having a lug engageable with said notch and adapted to be brought into registration with said extension to prevent withdrawal of the key in the position assumed in the release of the 10 jaw or bolt.
2. In a lock, a casing, a jaw or bolt mounted therein and having a tubular pivot pin provided with an end extension, the latter having a notch at its outer end, studs 15 mounted upon said casing, a key hole plate secured to said studs and having a key hole of mutilated circular form provided with an arcuate extension overlying a portion of the outer end of said pivot pin, and a key 20 insertible within the outer end of said pivot pin and having a lug adapted to engage said notch and further adapted to be brought into registration with said arcuate extension to prevent withdrawal of the key 25 in the position assumed in the release of the jaw or bolt.

3. In a lock, a casing stamped from sheet metal and bent up into form, a laminated jaw or bolt the laminations of which are stamped from sheet metal and suitably secured together to form a unitary whole, a tubular pivot pin having a spline connection with said bolt and rotatably mounted in said casing and provided with an end extension, the latter having a notch at its 35 outer end, a key-hole plate secured to said casing and having a key-hole, the marginal wall of which is provided with an extension, and a key insertible within the outer 40 end of said pivot pin and having a lug engageable with said notch and adapted to be brought into registration with said extension to prevent withdrawal of the key in the position assumed in the release of the jaw or bolt. 45

In testimony whereof I affix my signature in presence of two witnesses.

GEORGE W. WELLS.

Witnesses:

FLORENCE I. SMITH,
MARTIN F. CONNELLY.
